Samuel White Adams County Pennsylvania.

Silvers Patent

The schedule referred to in these Letters Patent and making part of this
same containing a description in the words of this said Samuel White
of his Improvement in the machine for hustling and cleaning Silver Lead.

To all whom this presents that comes to it known that Samuel White
of Adams County in the State of Pennsylvania has invented or discovered
a new and useful improvement in the machine for hustling and clean-
ing Silver Lead and that the following is a full and exact description
of the construction and operation of the same, as invented or dis-
covered by me, to wit: There will be a frame constructed in any convenient
shape, the upper part of which will be curved or bent out, upon the sides
and ends so that it will form a bay or court open at top and bottom.

There will be two revolving cylinders
of any convenient length and diameter fixed on a rod placed across
the middle of the frame or court. Immediately back of said cylinders
at each end of said frame or court there will be concaves, one being
within each end of said frame of such curve as will fit to the sides
of the cylinders. The cylinders and concaves may be made of cast iron, or
other metals, or of wood coated over with ebony or fixed with steel or iron
pins or teeth. The cylinders and concaves may be covered with steel
coated or fixed that the teeth shall point with the motion of the cylinders, that
is to say, when the cylinders are in motion the said teeth shall move
from forward, and the teeth on the concaves shall point in the same
direction as the teeth on the cylinders where they are in contact with the
concaves. There will be a hopper fixed to contain the silver lead or
bulbs immediately over the cylinders. There may be a riddle or riddles as
a pan under the drum (moved by the same power which turns
the cylinders) with which the lead may be cleaned as the drum (in
which it is huddled) is turned. If preferred the machine may be made without

Said cylinder and face, and the said, shall be a separate machine. The machine may be moved by hand or water-house, or other power may be employed. The power may be communicated to the machine, in any convenient manner so that it shall cause the cylinders to revolve in opposite directions—that is to say the two cylinders shall be from each other on the top or upper side, and on the bottom by the concave.

One of the various plans by which this may be communicated to the machine is to have a shaft or axle to which the driving force is applied placed on the machine, and the cylinders which said shaft may be connected with the cylinders by means of pulleys and bands of strings—or by wheels and pinions so geared as to give the requisite motion to the cylinders.

The concave (placed as before mentioned) over the sides of the machine by the sides of the cylinders, will be so arranged with shores, wedges and other fixtures that they may be placed and held in any position necessary to be in contact with a little resistance from said cylinders. The parts believed to be new and designed as an invention or discovery in the use of the cylinders and the concave placed in the manner above mentioned, so as to turn from each other on the top—and the plan of placing the concave above described, the both on the concave and cylinder pointing in the same direction and also the plan of causing the cylinders and concave to turn as above mentioned.
